CLAIM

The ornamental design for an electric toothbrush, as shown and described.

DESCRIPTION

FIG. 1 is a front perspective view of a first embodiment of an electric toothbrush, showing my new design; FIG. 2 is a rear perspective view thereof; FIG. 3 is a front view thereof; FIG. 4 is a rear view thereof; FIG. 5 is a left side view thereof; FIG. 6 is a right side view thereof; FIG. 7 is an enlarged top view thereof; FIG. 8 is an enlarged bottom view thereof; FIG. 9 is a front perspective view of a second embodiment of an electric toothbrush; FIG. 10 is a rear perspective view thereof; FIG. 11 is a front view thereof; FIG. 12 is a rear view thereof; FIG. 13 is a left side view thereof; FIG. 14 is a right side view thereof; FIG. 15 is an enlarged top view thereof; FIG. 16 is an enlarged bottom view thereof; FIG. 17 is an enlarged detail view of area 17 in FIG. 1; FIG. 18 is an enlarged detail view of area 18 in FIG. 1; FIG. 19 is an enlarged detail view of area 19 in FIG. 2; FIG. 20 is an enlarged detail view of area 20 in FIG. 9; and, FIG. 21 is an enlarged detail view of area 21 in FIG. 10. The broken lines in the drawings illustrate the portions of the electric toothbrush, which form no part of the claimed design.

The dash-dot-dash broken lines encircling the enlarged views are for annotative purposes only and form no part of the claim thereof.

1 Claim, 21 Drawing Sheets
